UNITED STATES PATENT OFFICE.

HUBERT L. JUDD, OF BROOKLYN, NEW YORK.

DESIGN FOR A PICTURE-NAIL HEAD.

Specification forming part of Design No. 5,252, dated September 5, 1871.

To all whom it may concern:

Be it known that I, HUBERT L. JUDD, of Brooklyn, in the county of Kings and State of New York, have invented and produced a new and original Design for the Heads of Picture-Nails; and the following is declared to be a correct description of the same.

My design relates to the shape or configuration given to the edge of the sheet metal which encircles or surrounds the base of the porcelain or other ornamental head of the nail.

In the drawing, Figure 1 is an elevation of the picture-nail head, showing my improved design for the edge of the sheet metal; and Fig. 2 is a side view of the same.

a represents the ornamental head, of porcelain or other material, and the same may be of the

desired shape or design. *b* is the sheet metal to receive the edge of said head *a* and hold the same by the ornamental scallops *c*, which are turned over and surround the base of said head *a*. The design or configuration given to this edge *c* is shown in the drawing, the same consisting of a series of scallops.

I claim as my invention—

The design of the metallic rim that receives the head *a*, the same being formed with a scalloped edge, as shown.

Signed by me this 28th day of July, A. D. 1871.
HUBERT L. JUDD.
